UNITED STATES PATENT OFFICE.

WILLIAM J. JUDD, OF HILLSDALE, NEW JERSEY.

MIXER.

1,127,009.

Specification of Letters Patent.

Patented Feb. 2, 1915.

Application filed July 15, 1905. Serial No. 270,283.

To all whom it may concern:

Be it known that I, WILLIAM J. JUDD, a citizen of the United States, residing in Hillsdale, in the county of Bergen and State of New Jersey, have invented certain new and useful Improvements in Mixers, of which the following is a specification.

This invention relates to machines for mixing concrete mortar and other materials, such as illustrated in United States Patent granted to me Nov. 15, 1904, No. 775,242. In said patent is shown a cubiform barrel, mounted to revolve upon a single horizontal axis and provided with interior vanes or buckets which converge toward the axis of revolution at the discharge end of the barrel, and are so formed and disposed that during the revolution of the barrel in one direction the contents are mixed without discharging, while by turning the barrel in the opposite direction the mixed contents are discharged.

The object of my invention is to improve the construction and operation and reduce the cost of the machine, and particularly to avoid the necessity of stopping and backing the barrel when it is desired to discharge. The barrel-reversing mechanism is dispensed with, and the time occupied in starting and stopping of the barrel is saved so that the barrel may be kept in rotation in a single direction for an indefinite time, and repeatedly charged and discharged without stopping.

Another object is to enable a larger charge to be mixed by the barrel at each operation.

In carrying out the present invention, I turn the barrel always backwardly, that is, in the direction for causing the same to be discharged; while I provide means for temporarily preventing such discharge. Such means preferably consist of a door closing the discharge end of the barrel and rotating therewith. During the revolution of the barrel, the mixture therein repeatedly slides down the buckets or vanes toward the mouth of the barrel, but does not escape, being turned back by said door into the body of the barrel. Owing to the additional agitation and churning of the mixture as it runs down the buckets and then out thereof and back into the body of the barrel, the material is much more rapidly mixed than is the case in the machine set forth in said patent. The door therefore is an important

element in effecting rapid mixing, since it enables the buckets to act not only as discharge buckets but also with great effect as mixing buckets. I also contrive to enable the barrel to mix about double the charge that could be accommodated by a barrel of the same size as described in said patent, since, owing to the use of the door, the barrel may be filled up far beyond the level of the discharge opening without liability of escape of material. I also contrive to form and mount the buckets so that they contact at their tips, whereby their discharge capacity is greatly increased.

Other objects and advantages will herein-after appear.

In the accompanying drawings, Figure 1 is a plan of a portable mixing machine made in accordance with my present improvements; an engine for driving the mixing barrel being indicated diagrammatically. In this figure the lower portion of the feeding hopper is shown in section. Fig. 2 is a side elevation of the mixing barrel and its appurtenances, showing the discharge door in full lines as open, and also showing in full and dotted lines means for locking said door closed. Fig. 3 is a vertical section of the apparatus taken at the axis of revolution of the mixing barrel. Fig. 4 shows on smaller scale an elevation and section of a triangular frame, such as used upon each end of the mixing barrel. Fig. 5 is a rear elevation, showing the discharge end of the mixing barrel. Fig. 6 is an end elevation; Fig. 7 a plan and Fig. 8 an edge view of a mixing and discharge bucket. Fig. 9 is an elevation of the mixing barrel showing the discharge end. Fig. 10 is a front elevation of the apparatus. Fig. 11 is a sectional view, Fig. 12 a rear elevation, and Fig. 13 a front elevation, of a feeding chute. Fig. 14 is a sectional elevation illustrating a modified closure for the discharge end of the apparatus.

The mixing barrel may be made in various shapes with sides sloping toward the axis of revolution at the discharge end of the barrel, but is preferably cubiform and comprises six sides numbered respectively 1, 2, 3, 4, 5, 6. It is mounted so as to revolve upon a horizontal axis designated as 7, said axis intersecting opposite apices of the cube, which is truncated at said apices. The cubiform barrel is mounted upon wheels 8

and 9, which ride upon two pairs of anti-friction rolls, one pair indicated at 10, 11, and the other at 12, 13; the first pair mounted upon an axle 14 and the second upon an 5 axle 15, each roll being keyed to its axle as at 16, so that the rolls in each pair must turn together, whereby easy and firm running of the large trundle wheels is assured. It will be seen that the rolls are of sufficiently 10 large diameter to enable the axles 14 and 15 to lie outside of the path of revolution of the cube. Flanges 17, 18 upon the trundle wheels prevent axial displacement of the barrel. Said axles 14, 15 are mounted 15 in bearings 19 upon a pair of sills 20, the latter connected by timbers 21 to form the bed portion of the framework. To effect revolution of the barrel, I provide upon the trundle wheel 9 an annular gear 22, meshing 20 with a driving pinion 23, to which is fixed a smaller pinion 24, the latter meshing with a still smaller pinion 25 fixed upon a driving shaft 26 of an engine 27, said shaft also having a fly wheel 28.

25 The materials to be mixed are placed in a hopper 29 at the receiving end of the barrel, said hopper provided at its bottom with a trap 30, which has a flange 31 inclosing the lower end of the hopper, and is hinged at 30 32 to the wall of the hopper, whereby the trap may be dropped to the inclined position as seen at 30^a, Fig. 3. Upon the trap is fixed a handle 33, which is provided with a toggle 34, connected at one end to the 35 handle and at the other end pivoted at 35 to the wall of the hopper. When the toggle is fully extended as seen in full lines at Fig. 3, it acts as a lock to hold up the trap 30. The toggle may be broken at any time, when the 40 trap will swing down as shown in dotted lines. This trap 30 when in the dotted-line position acts as an apron, fitting within an inclined chute 36, upon which the material of the hopper slides down into the mixing 45 barrel through a circular opening 37 in the receiving end of the barrel. Said circular opening 37 is formed in a triangular bracket 38, Fig. 4, having three bevel flanges 39 to fit over the edges of the cube where it is 50 truncated, said flanges being riveted to the sides of the cube as seen at 40, Fig. 3. This triangular frame 38 is fixed upon the inner face of trundle wheel 9, which is annular and provided with three interior ears, seen 55 at 41, Fig. 5, to which the corners of the triangular frames are secured by rivets at 42. The other truncated apex of the barrel is provided with a similar triangular frame 43, having a similar circular central opening 44 and secured in the manner already described in respect to the trundle wheel 8.

The bottom portion of the chute 36, which is formed of sheet metal, fits within a lower chute 44, the latter provided with a vertical 60 flange or plate 45, whereby it is secured to the rear side of a vertical guard plate 46, the latter secured between and upon a pair of upright angle-irons 47 fixed upon the framework. It will be seen at Fig. 3 that the lower lip 44^a of the chute 44 projects within 70 the circular opening 37 in the triangular plate or frame 38 which is fastened upon the truncated open end of the cubiform barrel. Upon the outer face of said plate 38 is provided a circular mouth-piece which is 75 coned to receive snugly said lip 44^a. It will thus be seen that the ingredients descend through the hopper and chute directly into the barrel and are prevented from fouling the moving parts. Within the opening 37 80 also extends a pipe 60 to supply the water necessary for the mixing; said pipe being suitably supported upon the framework. The mixing is effected by the turning over of the material, as it is thrown about from 85 side to side of the revolving barrel, and partly by means of a set of three blades 61, 62, 63 fixed within the barrel to revolve therewith in the direction shown by the arrow, Figs. 5 and 9. The blades are similar and symmetrically disposed about the axis of revolution 7, toward which they converge at their discharge ends, which are seen at Fig. 5 just within the circular axial opening 37 in the triangular frame 43. 90 Each blade or vane is secured edgewise against an adjoining side of the cube by means of ears 64, that is, to one of the three sides of the barrel that slope toward the apex at the discharge end. The blade or 95 vane 61 is secured to the side 3 and is about perpendicular thereto, and extends from the opening 37 to the opposite side 4 of the cube, to which it is secured by an ear 65. It will be seen that a box or bucket is formed by 100 the co-operation of the vane 61 with the adjoining sides 1 and 3 of the barrel, said bucket being closed by the other adjoining side 4 of the barrel. The bucket receives the mixture when at the lowermost portion 105 of its revolution, and holds the same during the rotation of the barrel until the bucket gets to its highest point. Then the material slips out of the bucket and falls either 110 back into the barrel again, thereby mixing the material, or else is discharged in a manner presently to be explained. It will be noted 115 that once in each revolution each bucket is at the lowermost portion of the barrel, and hence in position to drain the same. The three blades or vanes 61, 62 and 63 are similarly constructed and placed; and owing to their relative positions one is always picking up a charge of the contents of the barrel 120 while another is discharging, so that the mixing of the material in the barrel is rendered very effective. Each of the vanes is curved up along its free edge at one end, as at 66, forming a scoop for better retaining 125 the ingredients, and at their tips each of 130

said blades meets both of the others, as seen at Figs. 5 and 9. The turned up end of the scoop portion 66 of one blade matches or conforms to the body or flat portion of the 5 next, as seen at said figures. The blades are broad and capacious, and the opening at the discharge end of the barrel is sufficiently large to enable the same to discharge quickly. Owing to the direct meeting of 10 the tips of the blades, no space is wasted at the opening, thus conducting to rapidity of discharge.

In order to prevent discharge during the mixing operation, I close the discharge end 15 of the barrel by means of a gate or closure 67, which rotates with the barrel, but is pivoted upon the end of an arm 68, the latter hinged upon the framework at 69 and movable from the closed position at Fig. 3 20 to the open position at Fig. 2. When it is desired to discharge the mixture, it is only necessary to open said gate 67 which movement is effected by means of a lever 70, Fig. 2, connected by a link 71 to an arm 72 25 fixed upon a rock shaft 73 to which the arm 68 is also fixed. The door is held open by means of a latch 74, having a notch 75 to engage a projection 76 formed upon a short arm 77 of the lever. When it is desired to 30 close the gate, the latch 74 is lifted, and the lever 70 is pulled down to the dotted line position at Fig. 2. It will be seen that the link 71 forms a toggle with the arm 77, and that the toggle is closed during the downward swing of the lever 70, and carried slightly past the closing point to the position shown in dotted lines, whereby the arm 68 is locked down, and the gate held tightly 35 shut. Any suitable stop, as 78, may be provided for preventing further movement of the lever. Upon this end of the barrel I fix an annular discharge chute 79, said chute having one or more ears 80, whereby it is secured upon the triangular plate or 40 frame 43. The chute extends outwardly a great distance from the barrel, and makes it impossible for any of the material to fall upon the wheels or bearings; while owing to 45 its flaring annular form, it is capable of acting as a chute in all positions to which it may revolve. The gate 67 is provided with a peripheral flange 81, to fit the inner end of the chute. The gate is connected to the arm 68 by means of pivot 82, and is 50 also swiveled so as to be capable of slight vibration or tipping upon said pivot; the gate for this purpose having a hub 83, provided with an opening 84 to fit loosely upon the pivot 82; said opening, however, flaring from its center toward both ends, so as to enable the tilting of the cover relatively to the arm 68. Hence the gate is sure to fit tightly in the chute 79 under all circumstances.

65 In operation, the material to be mixed

is shoveled into the hopper 29; then the toggle 34 is broken and the trap 30 dropped, whereupon the material flows down the chute 36 into the revolving barrel, water being also admitted through the pipe 60. At 70 this time the discharge gate 67 is closed, the parts being in position seen in dotted lines at Fig. 2. As soon as sufficient material has entered the barrel, the handle 33 is pulled down, thereby closing the trap 75 30. As soon as the material is sufficiently mixed by the rotation of the barrel, the lever 70 is moved to the full line position at Fig. 2, thereby opening the gate or closure 67, whereupon the buckets or blades 61, as 80 the barrel continues to rotate discharge through the chute 79. This operation continues until the barrel is drained of its contents; and without stopping the barrel, the gate 67 may be closed and the trap 30 85 opened, so as to admit a fresh batch of material to be mixed. Thus the feeding, mixing and discharging may be conducted indefinitely without stopping the barrel.

In the form seen at Fig. 14, the arm 68^a 90 at the discharge end of the apparatus is provided with a closure in the form of a scoop 68^b, which in full lines is seen introduced within the annular chute 79 in position to receive and turn back into the barrel the 95 charges received by said scoop from the discharge buckets already described. By this form of closure or gate the ingredients may be somewhat more rapidly mixed, while a view is afforded to the attendant of the 100 contents of the barrel, so that he may open the closure to the dotted-line position and discharge the contents as soon as he sees that they are sufficiently mixed.

Other variations may be resorted to within the scope of the invention, and portions of my improvements may be used without others.

Having thus described my invention, I claim:

1. In a mixing machine, the combination of a revoluble mixing barrel having at one end a charge opening and at the other end a discharge opening, discharging blades within the barrel and converging to the 115 discharge end thereof, and tending constantly to discharge the contents of the barrel during the entire mixing operation, a closure fitted to the discharge opening of the mixing barrel and revolving therewith 120 to prevent the discharge thereof, and releasable means mounted upon a stationary part of the machine to be normally stationary during the rotation of the barrel and extending to said closure to hold the latter 125 in closed position.

2. In a mixing machine, the combination with a revoluble mixing barrel having at one end a charge opening and at the other end a discharge opening, the sides of the 130

barrel sloping toward said discharge opening, of a series of barrel-discharging buckets within the barrel, said buckets closed at their inner ends and converging to the discharge opening and tending constantly to drain off the contents of the barrel during the entire mixing operation, a closure fitting said discharge opening to revolve with the barrel and prevent the discharge thereof, and means mounted upon a stationary part 10 of the framework to be motionless during the revolution of the barrel and pivotally connected to the closure about at the axis of revolution of the barrel for opening and closing said closure, independently of any movement of the barrel.

3. In a mixing machine, the combination of a revoluble mixing barrel having at one end a circular discharge opening, a gate fitting said opening to revolve with the barrel, and an arm mounted upon a stationary part of the framework to be normally motionless during the revolution of the barrel, and pivoted to said gate about at the axis of revolution of the barrel and also swiveled to said gate in a manner to permit the same to vibrate slightly facewise to accommodate itself to said discharge opening.

4. In a mixing machine, the combination of a mixing barrel mounted for revolution and having charge and discharge openings at the axis of revolution, buckets converging to the discharge opening from the opposite sides of the barrel, a gate revolving with the barrel and closing said discharge opening, means upon a stationary part of the framework and normally stationary during the revolution of the barrel for opening and closing the gate independently of any movement of the barrel.

5. In a mixing machine, the combination of a mixing barrel mounted for revolution and having a discharge opening at the axis of revolution, the sides of said barrel sloping toward said discharge opening, barrel-discharging blades converging to said discharge opening and closed at their inner ends, said blades tending constantly to discharge said barrel during the mixing operation, an annular flaring discharge chute fixed upon the end of said barrel around said discharge opening and provided with a closure to overcome said tendency and to revolve with the barrel, and means mounted upon a stationary part of the machine and normally stationary during the rotation of the barrel and extending to said closure to control the same.

6. In a mixing machine, the combination of a mixing barrel mounted for revolution and having a discharge opening at the axis of revolution, the sides of said barrel sloping toward said discharge opening, blades converging to said discharge opening and tending constantly to discharge the contents

of the barrel, an annular chute fixed upon said barrel around said discharge opening, a gate within said chute and releasably secured in said opening to revolve with the barrel, and to prevent discharge of the contents of the barrel, and means mounted upon a stationary part of the machine and normally stationary during the revolution of the barrel and extending to said gate to control the same.

7. In a mixing machine, the combination of a mixing barrel mounted for revolution and having a discharge opening at the axis of revolution, the sides of said barrel sloping toward said discharge opening, buckets converging to said discharge opening and closed at their inner ends, and an annular chute fixed upon said barrel around said discharge opening; a gate within said chute closing said opening, an arm pivoted upon the framework and extending within said chute and pivotally connected to said door, and means for mechanically holding said door either closed or open by means of said arm.

8. In a mixing machine, the combination of a mixing barrel mounted for revolution and having a discharge opening at the axis of revolution, the sides of said barrel sloping toward said discharge opening, buckets converging to said discharge opening and closed at their inner ends, a gate for closing said opening; an arm pivoted upon the framework and pivotally connected to said gate, a lever connected to said arm, a releasable latch engaging said lever to hold the gate open, and means controlled by said lever for locking the gate closed.

9. In a mixing machine, the combination of a mixing barrel mounted for revolution and having a discharge opening, buckets converging to said discharge opening, a gate closing said opening; an arm pivotally connected to said gate, a rock shaft mounted upon the framework, said arm fixed to said rock shaft, a lever also mounted upon the framework, a link connecting said lever to a second arm upon said rock shaft; said lever and link being so mounted as to act as a toggle for springing the gate shut and locking it in its closed position, and a latch for holding the lever in position when the gate is open.

10. In a mixing machine, the combination of a revoluble mixing barrel having at one end a discharge opening, said barrel formed with three sides which slope toward the discharge opening, and vanes extending along the intersections of said sides in such a manner that each blade cooperates with the next side to form a bucket capable of discharging itself exteriorly of the barrel when the blade is above the axis of revolution, one side edge of each blade intersecting the body of the next blade at the end of

- the barrel, so that each of said blades directly meets or joins both of the others at their tips close to the axis of revolution.
11. In a mixing machine, the combination 5 with a mixing barrel and an inclined charging chute therefor, of a hopper above said chute and having a trap so hinged that when it is opened it may swing down and form an apron within said chute, a handle connected 10 to said trap, and means normally locking said trap closed; said locking means being in the form of a toggle extending from said handle to the wall of said hopper.
12. In a mixing machine, the combination 15 with a cubiform mixing barrel truncated at opposite apices, of a pair of annular wheels between which said barrel is disposed, a pair of triangular flat plates attached to said wheels and having bevel flanges receiving 20 the truncated ends of said barrel and secured thereto, and rolls upon which said wheels ran; said triangular plates having central openings through which the barrel is charged and discharged.
- 25 13. In a mixing machine, the combination with a cubiform mixing barrel truncated at its opposite apices, of a pair of annular wheels between which said barrel is disposed, rolls supporting said wheels, a pair 30 of triangular frames secured upon the inner sides of said wheels, and having bevel flanges receiving the truncated ends of said barrel and secured thereto, said frames having central openings, an annular cone-like mouth 35 constricted at its outer end and secured upon the outer side of one of said frames at the charging end of the barrel, and an inclined chute upon the framework and extending within said mouth and conforming closely 40 to the same, and discharging vanes mounted within the barrel.
14. In a mixing machine, the combination 45 with a cubiform mixing barrel truncated at its opposite apices, of a pair of annular wheels between which said barrel is disposed, rolls supporting said wheels, a pair of triangular frames secured upon the inner sides 50 of said wheels and having bevel flanges receiving the truncated ends of said barrel and secured thereto, said frames having central openings, an annular cone-like mouth 55 constricted at its outer end and secured upon the outer side of one of said frames at the charging end of the barrel, an inclined chute upon the framework and extending within said mouth and conforming closely to the 60 same, discharging vanes mounted within the barrel and converging toward the axis of
- revolution and meeting at their tips within the central opening in the other of said triangular frames, an annular discharge-chute 65 extending from said vanes and revolving with said barrel, and a gate within said discharge chute.
15. In a mixing machine, the combination 65 with a cubiform mixing barrel truncated at its opposite apices, of a pair of annular wheels between which said barrel is disposed, rolls supporting said wheels, a pair of triangular frames secured upon the inner sides 70 of said wheels and having bevel flanges receiving the truncated ends of said barrel and secured thereto, said frames having circular central openings, an annular cone-like mouth 75 constricted at its outer end and secured upon the outer side of one of said frames at the charging end of the barrel, an inclined chute projecting within said mouth, said chute provided with a vertical flange plate, a vertical guard-plate to which said flange 80 plate is secured, means supporting said screen and chute, and means for discharging the contents of the barrel through the opening in the other of said triangular frames.
16. The combination of a revoluble cubiform mixing barrel having at one end a charge opening and at the other end a discharge opening, discharge blades within the barrel and extending along the sides thereof, said sides and blades forming buckets, a discharge chute upon said barrel, said barrel being so mounted that said buckets in each revolution are carried above said chute but decline toward the same, to tend to discharge 90 themselves through said chute, a discharge-controlling part movable to different positions with respect to said chute, in one of which positions it prevents discharge from the buckets through said chute, and in the other of which positions said discharge 95 may occur, and manipulable means extending to a stationary part of the framework for shifting said discharge-controlling part from discharging to non-discharging position; whereby the barrel may be rotated in a 100 direction to discharge the contents, but such discharge may be prevented by adjusting said discharge-controlling part during the revolution of the barrel, whereby the cycle of charging, mixing and discharging may 110 be repeated without stopping the barrel.

WILLIAM J. JUDD.
